M. G. YEAGER,
ELECTRIC CURLER,
APPLICATION FILED MAR. 16, 1920.

1,424,546.

Patented Aug. 1, 1922.

INVENTOR

MARY GREEN YEAGER,
by James W. Hopkins, ATTORNEY.

UNITED STATES PATENT OFFICE.

MARY GREEN YEAGER, OF ST. LOUIS, MISSOURI.

ELECTRIC CURLER.

1,424,546.

Specification of Letters Patent. Patented Aug. 1, 1922.

Application filed March 16, 1920. Serial No. 366,242.

To all whom it may concern:

Be it known that I, MARY GREEN YEAGER, a citizen of the United States, residing at St. Louis, State of Missouri, have invented 5 certain new and useful Improvements in Electric Curlers, of which the following is a specification, reference being had therein to the accompanying drawing.

My invention relates to improvements in 10 electric curlers and has for its object to provide an apparatus for waving natural hair on the head, and has as its particular object to produce what is known as the Marcel wave.

15 In the drawings—

Fig. 1 is a longitudinal vertical view in mid-section of a curler embodying my invention.

Fig. 2 is a top plan view of the same.

20 Fig. 3 is a transverse sectional view of the same, taken on the line 3—3 of Fig. 2.

Fig. 4 is a similar view taken on the line 4—4 of Fig. 2.

The curler comprises a handle 5 having a 25 plate 6 which serves as a rest for the curler. Through the handle 5 the tubular sleeve 7 extends into the base 8 of the ferrule 9. The shell 10, of heat-conducting material is detachably mounted in the ferrule 9 by means 30 of set-screws 11. The inner shell 12 is seated in the shell 10, and contains the heating element 13, to which electric current is conveyed by the wires 14—14 extending through the tubular sleeve 7 as shown in 35 Fig. 1.

A heat non-conducting base 15 is secured to the sleeve 12 by means of the clamp 16 (see Fig. 3), the clamp 16 being secured to the sleeve 12 by means of the set screw 17 40 (see Fig. 1).

The sleeve 12 is provided with a series of prongs 18 which are arranged as shown in two straight lines, the prongs 18 in each line being equi-distant from each other, and 45 those in one line being in staggered relation to those in the opposing line, their arrangement and disposition being illustrated in Figs. 1, 2 and 3. The prongs 18 are of a heat conducting material and terminate 50 in the globular closures 19, whose screw threaded extensions 20 are seated in the open

mouths of the prongs 18, said prongs 18 being tubular and screw-threaded to receive said extensions 20. The caps 19 are of heat non-conducting material.

The tool thus described is used to wave the hair upon the head, and the base 15 rests upon the scalp of the person whose hair is being curled, when the portion of the hair near the scalp is being treated. In the treatment of long hair at points more remote from the scalp the curler rests upon any suitable support, being held against rotation by the square lower face of the base 15 and the straight edge of the plate 6. The 60 effect known as the Marcel wave is produced by winding the hair alternately around the prongs 18 comprised in the two series above described and illustrated; the prongs 18 being heated as well as the sleeve 12, the heat 65 so administered serves to impart the desired Marcel wave effect.

The construction described may be varied in detail without departing from the spirit of my invention, whose primary object is to 70 provide the electrical sleeve 12 with the heated prongs 18, said prongs being alternately disposed in the arrangement which I have described. More than two lines or 75 series of the prongs 18 may be employed if desired; the two lines illustrated being used as the preferred form of my invention, with a view to lightness and compactness.

As shown in Fig. 3 the two lines of prongs 18 are mounted tangentially with reference 80 to each other.

Having thus described my invention what I claim as new and desire to have secured to me by the grant of Letters Patent, is—

As a new article of manufacture, an electric curler comprising a heat non-conducting base; a shell of heat-conducting material; a clamp securing said shell to said base; a heating element seated in said shell; a ferrule wherein said shell is detachably 90 mounted; a handle; a tubular sleeve extending through said handle and into said ferrule; and a plate secured to said handle and arranged to hold the curler against rotation.

In testimony whereof I hereunto affix my 100 signature.

MARY GREEN YEAGER.
